RADIO TRANSMITTING SYSTEM

Felix Gerth, Berlin-Tempelhof, and Ernst Kramar, Eberswalde, near Berlin, Germany, assignors to C. Lorenz Aktiengesellschaft, Berlin-Tempelhof, Germany

Application May 10, 1930, Serial No. 451,330, and in Germany June 6, 1929

6 Claims. (Cl. 250—17)

Applications have been filed in Germany June 6, 1929; Austria April 7, 1930; The Netherlands April 10, 1930; and Italy April 16, 1930.

In the art of transmitting directed rays by means of so-called sparking beacons, as is well known, two directing aerials or systems of aerials situated perpendicularly to one another are excited alternately in such a manner, that the pause of the signals emitted by one aerial, is filled out by the signals transmitted by the other antenna. Owing to the diagram of radiation of the directed transmitting apparatus there exist some lines in space, on which the signals of both systems of aerials are received with an equally intense energy. Provided a suitable choice of the letters is made, mostly the signals — . and . — are selected, the signals will merge on said line of equal energy into a continuous dash, that is to say, the pauses of the one signal are filled out by the other signals.

But the occurrence of said continuous dash is dependent on the condition, that the antennas are connected and disconnected at the same time without any retardation. Tests made with the end in view to carry through such a switching by means of relay arrangements, have not been successful owing to the periods of actuation required by the arrangement of the relays. For that reason two main transmitting devices were alternately operated by a key together with a common controlling transmitting apparatus, in consequence of which the difficulties with the relays were overcome, however such apparatus is rather bulky.

According to this invention the described disadvantages are avoided, in that the energy supplied to the various directing aerials or systems of aerials respectively from the high frequency generator, is keyed alternately by means of two choking coils, having two key windings connected in series. One of these choking coils is preliminarily magnetized with an additional winding. That circuit comprising the preliminarily magnetized choking coil, will supply the high frequency energy to the appurtenant system of directing aerials owing to the small inductive resistance of the choking coil. This preliminary magnetization is neutralized by the key winding provided thereon and simultaneously the other one of the two choking coils is magnetized, since both the key windings are connected in series. Owing to this fact now high frequency energy is supplied to that system of aerials, which did not transmit, while the other system of aeri-

als which did transmit up to that time, is not supplied with energy.

The subject matter of the invention will be more clearly understood with the aid of the accompanying drawing, in which

Figure 1 is a diagrammatic view of the arrangement according to the invention, and

Figures 2a and 2b are diagrammatic views of the direct current windings of the choking coils.

The high frequency energy is supplied from the transmitting apparatus to the key-instrument by way of the inductance L_1 . An additional inductance L_2 is coupled with L_1 to which two circuits are connected, which are each in connection with a directing system. It is immaterial here, whether a single directing aerial is concerned or a voluminous system of directing aerials. One of the branches (I) is formed by L_2 , the capacity C_1 , the inductance L_3 (C_1 and L_3 are arranged for tuning purposes), L_4 , C_2 , L_5 and the winding W_1 of the choking coil D_{r1} . The other branch (II) consists of the elements L_2 , C_1 , L_3 , L_5 , C_3 , L_6 and W_2 . The inclusion of condensers C_2 and C_3 in the respective parts of the circuits I and II individual thereto enable the such parts to be separately tuned and thus improve the operation of the system. The systems of aerials are coupled with the inductivities L_4 and L_5 by way of L_7 and L_8 . The choking coils are provided with iron cores, upon which additional windings are wound. Both the key windings W_3 and W_4 on the choking coil D_{r1} and D_{r2} respectively are connected in series by the interposition of the key T, which in a given case may at the same time be utilized for transmitting the signals, and in the circuit of said device is situated the source B of direct current. The choking coil D_{r2} in addition is provided with a permanent magnetizing winding W_5 , which is directly connected with the battery B through the interposition of a regulating resistance. The mode of action of the arrangement is as follows.

If the key T is open, the choking coil D_{r2} is preliminarily magnetized by means of the permanent magnetizing winding W_5 , that is to say, in consequence of the small inductive resistance of the choking coil D_{r2} the high frequency energy emitted by the transmitting device is supplied through the circuit II to the system of aerials connected at L_8 . The system of aerials connected at L_7 receives no energy at that moment, since the choking coil D_{r1} is under no preliminary magnetization. As soon as the key T is depressed a direct current will flow through the windings W_3 and W_4 . By this means the chok-

ing coil D_{r1} is magnetized and the transfer of high frequency energy is effected by the circuit I, since at the same time the permanent magnetizing current in the choking coil D_{r2} generated by W_5 is compensated by the winding W_4 . The windings of the choking coils must be particularly adapted for that purpose.

The direct current windings of the choking coils are again represented in Figure 2. The 10 choking coil D_{r1} is illustrated in Figure 2a. Upon the iron core E_1 are arranged two windings, through which direct current will flow. The high frequency windings are not shown in the drawing for the sake of clearness. In order to maintain the heating of the key choking coils caused by the direct current in the various windings and the fluctuations of the direct current caused thereby in both choking coils at a constant value, according to a further feature of the invention 15 also the choking coil D_{r1} is provided with a compensating winding consisting of two halves, which are differentially connected, so that, while the winding produces a heating effect, its net magnetic effect upon the core is nil. For that 20 purpose an additional winding W_6 is mounted on the shanks besides the key winding W_3 proper, which normally is secured to the iron core E_1 . Windings W_6 and W_3 are wound in the same direction on the left shank of the core E_1 and in 25 the opposite direction on the right shank, as shown in Fig. 2. On account of this arrangement the magnetizations caused by the winding W_6 are compensated in the iron core, so that only the key winding W_3 proper of the choking 30 coil will remain active. In the choking coil D_{r2} illustrated in Figure 2b the key winding W_4 and the permanent magnetizing winding W_5 are mounted in such a manner, that during the flow of direct current through the key winding W_4 35 the magnetization of both windings will be compensated. The arrows of current shown in the drawing indicate the instant at which the choking coil will be key-operated, so that the circuit II will not supply any current to the system of 40 aerials connected at L_8 .

If the circuits I and II are tuned between the 45 points of their connection, that is to say those parts of the circuits, which are not formed in common by L_2 , C_1 , L_3 by means of condensers C_2 and C_3 respectively to the frequency supplied, there obtains at the choking coils the least possible 50 voltage, which corresponds to the value of the ohmic voltage. In practical operation such tuning is carried out in that the circuits L_2 , C_1 , L_3 , L_4 , C_2 , L_6 , W_1 ; and L_5 , C_3 , L_6 , W_2 are tuned 55 separately from one another and then connected.

We claim:

1. A radio transmitting system comprising two 60 antennæ, a source of radio frequency energy, coupling circuits between said source and said antennæ, and means to render said coupling circuits alternatively effective to transfer energy to one or the other of said antennæ, said means comprising a keying device so inductively coupled to said coupling circuits that upon closure or opening of the contact of said device the impedances of said coupling circuits are varied oppositely.

2. A radio transmitting system according to 65

claim 1, characterized in this that each circuit contains a choke coil having a core, and said means includes a winding on one choke coil core connected in circuit with a source of direct current, a winding on each choke coil core connected in series, and a circuit closer to close circuit from said source of direct current through the serially connected windings in a direction whereby said two windings on the same core are rendered differential in their effect upon said core.

3. A radio transmitting system comprising two 80 antennæ, a source of radio frequency, a coupling circuit for each antenna coupling it to said source, a choke coil having a core for each coupling circuit having a winding thereon, one of the choke core coils having a second winding connected in circuit with a source of direct current and a third winding connected to said direct current source and differentially with respect to said second winding, and said other choke core coil having a second winding connected in series with said third winding, and a circuit closer arranged to open and close circuit from said direct current source through said serially connected windings.

4. A radio transmitting system comprising two 90 antennæ, a source of radio frequency energy, coupling circuits between said source and said antennæ, and means to render said coupling circuits alternatively effective to transfer energy to either of said antennæ before effective transfer of 100 energy to the other is interrupted, said means comprising a keying device so inductively coupled to the said coupling circuits that upon operation thereof the impedance of one circuit is increased whilst that of the other is decreased.

5. In a radio transmitting system comprising two 110 antennæ, a source of radio frequency energy, coupling circuits between said source and said antennæ which normally prevent the radio frequency energy from being simultaneously and 115 effectively transferred to said antennæ, and means to render said coupling circuits alternatively effective to transfer energy to one or the other of said antennæ, said means comprising a keying device so inductively coupled to said coupling circuits that upon closure of the contact of said device the impedance of one coupling circuit is decreased whilst the impedance of the other coupling circuit is increased.

6. A radio transmitting system comprising two 125 antennæ, a source of radio frequency energy, coupling circuits between said source and said antennæ, each coupling circuit being formed by a path individual thereto and a path common to the two circuits and each path containing inductance and capacity tunable to the frequency of 130 said source, and means to render said coupling circuits alternately effective to transfer energy to one or the other of said antennæ, said means comprising a keying device so inductively coupled to said individual paths that upon the opening of the contact of said device one coupling circuit is rendered operative for transfer of energy whilst simultaneously the other coupling circuit is rendered effectively inoperative for transfer of 140 energy.
